UNITED STATES PATENT OFFICE

HENRY R. TROTTER, OF CHICAGO, ILLINOIS, ASSIGNOR TO HACKER MANUFACTURING COMPANY, OF CHICAGO, ILLINOIS, A CORPORATION OF ILLINOIS

PRINTING PRESS

Application filed December 10, 1928. Serial No. 324,926.

My invention relates to printing presses that employ complementary printing members at least one of which is in the form of a rotating cylinder, the printing form being carried by one of said members and being subject to printing pressure from the other member. The invention has for its object the provision of an improved assemblage of a frisket with such a press in conjunction with controlling means for the frisket whereby its adjustment with respect to the form may be automatically controlled. As I have embodied my invention the press may be operated as simply as though the frisket were absent. The present invention is an improvement upon the invention forming the subject matter of my co-pending application Serial No. 324,925 filed of even date herewith.

In carrying out the invention disclosed in my aforesaid co-pending application, I interpose the frisket between the printing members and space a portion of it from the form bearing printing member and pass this portion between the cylinder and the inking mechanism if such be employed. In the specific embodiment of the invention of said co-pending application, the frisket is provided with relatively movable anchorages at its ends. In carrying out my present invention the frisket is mounted, at its ends, upon relatively fixed anchorages. In the preferred embodiment of the invention the cylinder turns upon a fixed axis in each of its operations, the printing member complementary thereto is in the form of a reciprocating bed, to the ends or longitudinally spaced apart portions of which the ends of the frisket are attached, and the inking mechanism and the cylinder are normally spaced a substantially unchanging distance apart. The frisket is desirably in the form of a flexible sheet which is readily conformable to the curvature of the cylinder, a positioner being provided for the frisket intermediate its ends that maintains the aforementioned frisket portion spaced apart from the inking mechanism and the form bearing member.

I will explain my invention more fully by reference to the accompanying drawings in which Fig. 1 is a longitudinal elevation, partially in section of a press equipped in accordance with my invention; Fig. 2 is a plan view of the press shown in Fig. 1; Fig. 3 is a simplified view, partially in section, and essentially diagrammatic, portions being removed; and Fig. 4 is a view similar to Fig. 3 but showing parts in changed positions.

The main supporting frame 1 of the press includes a suitable pedestal 2. Upright supports 4 carry the rotating shaft 6 of the printing cylinder 7, these supports defining a substantially fixed axis of rotation for the cylinder in the printing and non-printing operations. It is to be understood, however, that the invention is not to be limited to a cylinder whose axis is thus fixed. The press illustrated is a hand operated proof press and when the invention is embodied in such a press a hand crank 8 is provided upon the shaft 6 for turning the cylinder. Bearer rollers 9, having fixed axes, are supported by the frame 1 and support the reciprocating printing bed 10, this bed being adapted to carry the employed printing form 11 of any suitable character.

The printing cylinder is provided with the usual bearers 13 at the sides of the press and the bed is provided with the usual bearers 13'; also at the sides of the press, upon which the bearers 13 roll as the bed is moved in each printing operation, these bearers, when contacting, defining the normal printing space between the printing members 7 and 10. The printing cylinder is lowered for the printing stroke and raised for the non-printing stroke, the cylinder when lowered exerting printing pressure upon the paper sheet that is passing between the two printing members. Any suitable mechanism may be employed for raising and lowering the

cylinder. The mechanism illustrated includes a shaft 14 which has a fixed axis of rotation upon the frame of the press. This shaft carries circular cams 15 that are eccentric to the shaft. These cams work within elongated openings 16 that are formed in the upright cylinder supports 4 which are directly carried by said cams. A handle 17 is fixed upon the shaft 14 whereby the cylinder supports 4 may be lowered and elevated to bring the cylinder into and out of printing relation to the form.

Any suitable form of inking mechanism may be employed. The inking mechanism illustrated is inclusive of the inking rollers 18 which are carried upon the side supports 19, these side supports being bolted to the frame of the press in case the inking mechanism is to be held stationary to be normally spaced a substantially unchanging distance from the cylinder.

The frisket 20 has one or more openings 21 therethrough to permit the sheet that is to be printed upon to contact with the form 11. This frisket is provided with relatively fixed anchorages at its ends. It is preferably anchored to the ends of the reciprocable bed 10. The left hand end of the frisket is secured to said bed at its level. The other end of the frisket is attached to a bar 22 upon posts 23 that are carried by the bed and serves to elevate the portion of the frisket to the right of the cylinder above the bed. The frisket is preferably a flexible sheet that is readily conformable to the curvature of the cylinder where it passes between the cylinder and the bed. A positioner, in the form of a roller 24 that is journaled upon the upper ends of the side supports 19, engages the frisket between its ends, being so located as to maintain the portion of the frisket that is between the cylinder and the inking mechanism spaced apart from the inking mechanism. The bed causes the frisket to travel therewith. The frisket opening 21 and the inking mechanism are so inter-related that the inking mechanism may ink the form without interference from the frisket portion that is above it and so that the frisket may be applied to the form without interference from the inking mechanism, these results being automatically effected during the operation of the press. In effect the frisket is automatically elevated to clear the inking mechanism during the form inking operation and is automatically lowered in preparation for and during the printing stroke. The printing cylinder gradually lays the frisket upon the form as the printing proceeds and gradually permits elevation of the frisket during the non-printing stroke.

I claim:

A printing press including two cooperating printing members between which the sheet to be printed upon is received, one of

said members being a rotatable cylinder, the printing form being carried by one of said members and being subject to printing pressure from the other member, a frisket interposed between said printing members and having relative fixed anchorages at its ends, and frisket positioning means, said means including said cylinder.

In witness whereof, I hereunto subscribe my name.

HENRY R. TROTTER.
